UNITED STATES PATENT OFFICE.

HENRY T. O'SHIELDS, OF ATLANTA, GEORGIA.

NON-FREEZING HYDRANT.

1,297,001.

Specification of Letters Patent. Patented Mar. 11, 1919.

Application filed July 10, 1916. Serial No. 108,445.

To all whom it may concern:

Be it known that I, HENRY T. O'SHIELDS, a citizen of the United States, residing at Atlanta, in the county of Fulton and State 5 of Georgia, have invented new and useful Improvements in Non-Freezing Hydrants, of which the following is a specification.

This invention, from a generic aspect, pertains to hydrants, but it more specifically 10 comprehends those of the anti-freezing type having facilities for automatically discharging the fluid remaining in the stand pipe, after termination of the service flow.

The fundamental object of this invention 15 is to provide a hydrant of the character designated, having a secondary valve controlling the inlet orifice of an eduction pipe and automatically operable to a closed position during the period of service flow, and 20 to an open position when such flow is discontinued, to effect a drainage of the residue fluid which, during extreme climatic conditions, either becomes stagnant, germ impregnated, and consequently, a menace 25 to health, or freezing causes bursting of the stock, and other annoying hydrant difficulties.

Further objects of this invention are to 30 design a hydrant having a secondary valve, the open or closed position of which depends entirely upon hydraulic pressure, said valve being so disposed as to automatically resume an open position simultaneous with the termination of the service flow; and 35 finally one simple in construction, efficient in operation, containing few parts which may be conveniently assembled and disassembled for the purpose of installing or making necessary repairs.

Briefly stated, this invention comprises 40 a stock having its upper end communicating with a discharge faucet, and its lower end with a service main, a main ball valve located at the lower extremity of the stock, 45 and operable to open and closed positions by a vertically reciprocating stem passing through the stock and connected at its free end by a suitable operating means, and a secondary ball valve juxtaposed with 50 respect to the main valve and controlling the inlet orifice of a drain or eduction pipe, the construction and arrangement of said secondary valve being such that, while the supply is sufficient to operate the latter to a 55 closed position, the pressure exerted by the column of residue fluid in the stock subse-

quent to closing of the main valve is insufficient to operatively maintain said valve, in consequence of which it will assume an inoperative position, and permit the residue 60 fluid to drain from the stock.

In the accompanying drawings, in which corresponding parts are indicated by similar reference characters:—

Figure 1 is a transverse vertical section of 65 my improved anti-freezing hydrant, with parts being shown in elevation, and the valve in inoperative position; and

Fig. 2 is an enlarged sectional view in detail, illustrating the secondary valve in a 70 partially closed position.

In the illustrated embodiment characterizing this invention, there is shown a hydrant built up of a plurality of sections, including a relatively elongated, cylindrical 75 section 1, externally threaded or otherwise formed at its end to receive the T shaped capping union 2, the latter having internally threaded diametrically opposed openings 3 and 4 to receive an externally 80 threaded discharge nozzle 5, and the similarly threaded end of a suitable bushing 6 rotatably housing a shaft 7. On the outer end of shaft 7 is affixed a handle 8, or other suitable operating means. A disk 9, integrally formed with the inner end of shaft 7, carries an eccentrically positioned, laterally extending pintle 10, connected to the upper extremity of valve stem 11, while the lower extremity of the latter, which is externally threaded, adjustably supports a main ball valve 11' adapted to seat in the lower end of intermediate union 12, for this purpose formed with an internal seat 12'. This union affords a connection between the 85 lower extremity of stock 1 and one end of elbow 13, the other end thereof communicating with supply pipe W. The ball valve 11' may be constructed of rubber or metal, dependent on the exigency of the situation, 90 as will be readily understood without further discussion. A spider 14, integrally formed with the lower end of stock 1, functions as a guide during the operation of seating and unseating the valve. 95

Communicating with the union 12 and extending upwardly and outwardly therefrom, is a nipple 15, internally threaded contiguous its outer end to receive the externally threaded valve plug 16, which is formed with a 100 valve chamber 17, said chamber having its lower end closed by a guide plug 18, provided 105

with transversely extending diametrically opposed passages 19, for a purpose hereinafter to be explained. An opening 20, located intermediate passages 19, accommodates the 5 valve stem 21, integrally formed with a secondary ball valve 22, operatively located within the valve chamber 17. The wall of plug 16 surrounding the upper end of chamber 17, is arcuate in contour, affording a seat 10 23 for the valve 22, when the latter abuts opening 24, within which is positioned the inlet end of an eduction or drain pipe 25. The stem 20 of the valve 22 directs its seating and unseating movement through the 15 chamber 17, and effects proper seating. Plug 16 and its incident valve structure, are protected by a hood 26, threaded on the stock 1 adjacent its lower end, as clearly shown in Fig. 1 of the drawings.

20 A hydrant, constructed in accordance with the above, operates as follows:—

Presuming the main valve 11' to be in a closed position, as shown in Fig. 1, rotation of the operating means will downwardly actuate valve stem 11 and, unseating the valve connected therewith, permit the supply fluid to pass upwardly through the stock and discharge through the nozzle 4. As the supply fluid ascends the stock, it will enter passages 19 and, seating valve 22, close the inlet orifice of eduction pipe 25. Upon restoring main valve 11' to its initial position, thus discontinuing the service supply, the pressure exerted by the column of residue 25 fluid in the stock being insufficient to maintain valve 22 in its seated position, it will drop to an inoperative position, as shown in Fig. 1 of the drawings, and, opening the inlet orifice of eduction pipe 25, permit the 30 residue fluid to pass through passages 19, chamber 17, and thence through said pipe 25 to any desired point. Of course, in this connection, it is obvious, owing to the weight of valve 22 and its angle of location, it will 35 readily respond to the supply or head pressure, while on the other hand, the weight of the column of residue fluid being much less than the head pressure, and incapable of maintaining said valve in closed position, 40 will permit it to assume an inoperative one.

50 From the foregoing structural outline, it will be seen I have designed an anti-freezing

hydrant of an extremely simple nature embodying but few parts, and a secondary valve construction which may be readily applied to any standard hydrant to effectively drain the latter of its usual column of residue fluid. 55

Although in the foregoing, I have set forth certain elements as best adapted to perform the functions allotted to them, nevertheless it is to be understood, various minor changes as to form, substance, etc., may be resorted to within the scope of the appended claims, without departing from or 60 sacrificing any of the principles of this invention. 65

Having now described my invention, what I claim is:—

1. In a hydrant, the combination with a 70 stock including an upwardly and outwardly projecting tubular extension; of a plug closing the outer end of said extension, said plug having therein a valve chamber communicating at its upper extremity with an 75 outlet orifice, a guide plug closing the inner end of said chamber and having therein a passage establishing a communication between said chamber and stock, and a ball valve situated in said chamber and operable 80 to a position closing said orifice by the supply pressure, substantially as and for the purpose set forth.

2. In a hydrant, the combination with a 85 stock including an upwardly and outwardly projecting tubular extension; of a plug closing the outer end of said extension, said plug having therein a valve chamber communicating at its upper extremity with an outlet orifice, a guide plug providing a closure for the lower end of said valve chamber, said plug having therein a plurality of 90 passages establishing communication between the interior of said chamber and that of said stock, a ball valve located within 95 said chamber and operable by the supply pressure to a position closing said orifice, and means in connection with said valve to direct the movement of the latter, substantially as and for the purpose set forth.

HENRY T. O'SHIELDS.
